ATTORNEY.

UNITED STATES PATENT OFFICE

161,319

FIGURINE

Paul Newton Cope and Theodosia Lee Cope,
Santa Ana, Calif.

Application July 2, 1949, Serial No. 3,684

Term of patent 3½ years

(Cl. D29—23)

To all whom it may concern:

Be it known that we, Paul Newton Cope and Theodosia Lee Cope, citizens of the United States, residents of county of Orange, State of California, have invented a new, original, and ornamental Design for a Figurine, of which the following is a specification, reference being had to the accompanying drawing, forming a part hereof.

Fig. 1 is a front view of a figurine, showing my new design;

Fig. 2 is a side view;

Fig. 3 is a rear view thereof.

We claim:

The ornamental design for a figurine as shown.

PAUL NEWTON COPE.
THEODOSIA LEE COPE.
